[57] CLAIM

The ornamental design for a personal computer keyboard template for displaying operating instructions for software program, as shown and described.

DESCRIPTION

FIG. 1 is a front, top and left side perspective view of a personal computer keyboard template for displaying operating instructions for software program showing my new design, the book being opened, and the keyboard being shown in broken lines for illustrative purposes only;

FIG. 2 is a top plan view thereof on an enlarged scale, the book being closed;

FIG. 3 is a front elevational view thereof on an enlarged scale;

FIG. 4 is a bottom plan view thereof on an enlarged scale;

FIG. 5 is a left side elevational view thereof on an enlarged scale;

FIG. 6 is a right side elevational view thereof on an enlarged scale.

The little book, which is an integral part of the personal computer keyboard template, is securely attached to the base of the template.

FIG. 1.

FIG. 2.

FIG. 3.

FIG. 4.

FIG. 5.

FIG. 6.
